Patented Feb. 13, 1917.

UNITED STATES PATENT OFFICE.

JOHN WARWICK GORDON, OF ST. CATHARINES, ONTARIO, CANADA.

TOY TARGET.

1,215,927.

Specification of Letters Patent. Patented Feb. 13, 1917.

Application filed April 6, 1916. Serial No. 89,357.

To all whom it may concern:

Be it known that I, JOHN WARWICK GORDON, of the city of St. Catharines, in the county of Lincoln, in the Province of Ontario, Canada, have invented certain new and useful Improvements in Toy Targets, of which the following is the specification.

My invention relates to improvements in toy targets and the object of the invention is to devise a target of this class which will automatically record hits and visibly indicate the record of each hit and it consists essentially of a target body having a series of concentric annular openings corresponding to the inner and outer rings of the target, scoring number indicator designed to move from an invisible to a visible position, mechanism operated by the weight of a marble or other projectile fired against the target for operating each number indicator independently, means for directing the marbles after passing through an annular opening of the target to a corresponding mechanism operating a number indicator and means for separately retaining the marbles scoring the same number of points together as hereinafter more particularly explained by the following specification.

Figure 1, is a general perspective view of my target.

Fig. 2, is a rear view of my target with the back board removed and the side partially broken away and in section.

Fig. 3, is a vertical section through the center of the target.

Fig. 4, is a diminutive perspective detail of the concentric members forming annular spaces on the face of the target and means for deflecting the marbles passing through the concentric openings formed by the members in the required direction.

In the drawings like letters of reference indicate corresponding parts in each figure.

1 indicates the target casing proper provided with a circular orifice 2 flared outwardly toward the inner face of the front wall of the casing. 3 indicates the back wall of the casing which extends downwardly below the casing 1 and is provided with a vertical slot 4 for a purpose which will hereinafter appear.

5 indicates a supplemental casing carried by the wall 3 at the back thereof. 6, 7 and 8 indicate a series of concentric members carried by the front face of the wall 3. The outer ends of the members 6, 7 and 8 are cir-

cular, the circular end of the member 8 corresponding to the bull's eye of the target, the space between the circular end of the member 8 and the circular end of the member 7 corresponding to the "inner" and the space between the circular member 7 and circular member 6 corresponding to the "outer" of the target. The lower portions of the members 6, 7 and 8 flare downwardly in an inclined direction, such outward flare gradually increasing toward the sides of the members so as to form a curve substantially parabolic in form. The back portions of the members 6, 7 and 8 extend downwardly in an inclined direction and are substantially flat between the ends 6' and 6² of the curved portion of the member 6 and 7' and 7² of the curved portion of the member 7 and points 8' and 8² between the curved portion of the member 8. By this means when looking from the front of the target the upper portion of the members 6, 7 and 8 show a forwardly presented inclined wall.

9 and 10 indicate deflectors extending between the wall of the member 7 and the wall of the member 6. These deflectors prevent the marbles passing directly through the space between the members 6 and 7 striking the back wall 3 of the target and rebounding outwardly again. The marble or other projectile passing through the opening at the side of the target strikes either the deflector plate 9 or 10 and is deflected downwardly into the pocket formed by the curved concentric portions of these members. The members 6, 7 and 8 are respectively provided with tongues 11, 12 and 13 which extend through the vertical slot 4. At the opposite side of the concentric members to the tongues 11, 12 and 13 are located deflecting pieces 14 and 15 which serve to deflect the marbles sidewise and prevent any chance of their rebounding or lodging there.

17, 18 and 19 indicate openings formed in the wall 3 below the casing 1. These openings are arranged as shown clearly in Fig. 2 vertically one above the other. 20 indicates an opening formed in the top of the casing 5. 22, 23 and 24 indicate a series of vertically slid able bars, each having a broad upper end 25 on the front face of which is indicated the numbers representing the points scored. The broadened ends 25 are separated apart by cross pins 26 so that they move upward freely one of the other. The bars 22, 23 and 24 are each provided with a

vertical edge notch 27 through which a cross pin 28 extends, such cross pin being held in the walls of the casing 5. The cross pin 28 holds the bars 22, 23 and 24 in vertical alinement, and takes the strain off the levers 29, 30, 31 if interfered with.

29, 30 and 31 indicate lever bars pivoted on pins 27^x, 28^x and 29^x. 32 indicates a screw pin which extends from the lower end 10 of each bar 22, 23 and 24. 33 indicates a notch formed in one end of each bar 29, 30 and 31 and through which the screw pin 32 extends so that the ends of the bars 22, 23 and 24 rest respectively upon the ends of 15 the levers 29, 30 and 31. 34 indicates a nut preferably semi-spherical in form which is threaded on to the screw pin 32 against the bottom of its respective lever.

It will be noticed on referring to Fig. 2 23 that the levers 29, 30 and 31 are located in the casing so that the central portion is substantially on a line with the inclined tongues 11, 12 and 13. The levers 29, 30 and 31 are normally slightly inclined from the end attached 25 respectively to the bars 22, 23 and 24 to the opposite end located in proximity to the orifices 17, 18 and 19.

It will be noticed that the end of the bar 29 is normally positioned above the orifice 30 17 and the ends of the lever bars 30 and 31 are normally just above the orifices 18 and 19 being held in this position by the pins 35, 36 and 37. The upward movement of the lever bars 29, 30 and 31 at the opposite end 35 of their pivots 27^x, 28^x and 29^x is limited by the pins 38, 39 and 40.

Although I have described the connection 40 between the levers 29, 30 and 31 and the bars 22, 23 and 24 as comprising the pin 32, nut 34 and notched end of the lever 33 it may be understood that any suitable pivotal connection may be provided which will allow of the free upward movement of the bars 22, 23 and 24.

45 41, 42 and 43 indicate inclined runways carried by the front face of the portion of the wall 3 depending below the casing 1. The bottom portions at the upper end of the runways 41, 42 and 43 are respectively each 50 located on a line with the bottom of the orifices 17, 18 and 19. 44 indicates a pin which extends vertically through the perforations 45 formed in the lower ends of the runways 41, 42 and 43. This pin 44 forms a 55 stop for the marbles 46 as they run down the runways 41, 42 and 43.

Having described the principal parts involved 60 in my invention I will briefly describe the operation of the same.

65 In order that the face of my toy target appears at a distance similar to the face of an ordinary target the interior of the space formed between the members 6 and 7 is blackened and the interior of the space formed between the members 7 and 8 is

whitened and the interior of the member 8 is blackened and the outer face of the casing 1 whitened. This provides that the bull's eye appears black and the outer appears black and the inner appears white according 70 to usual practice.

When the marble or other projectile which is fired from the toy cannon scores a bull's eye it passes through the center circular opening formed by the member 8 striking 75 the inclined back wall thereof being deflected downwardly thereby on to the tongue 11 carrying the marble through the slot 4 into the casing 5 on to the lever 29 at the side of the pivot 27^x opposite to the bar 24. The 80 end of the lever carrying the ball or marble is depressed until it comes normally into alinement with the bottom of the opening 17. By this operation the upper end of the bar 24 is raised so as to indicate the scoring 85 number corresponding to the score of the bull's eye. As the marble rolls down toward the inclining lever 29 it strikes the edge of and rings the bell 47^x and then passes onto the lever rolling down the same to the opening 17. The marble passes through the opening 17 and runs down the runway 41 against the pin 44 and is retained in the runway by such pin. Similarly if an inner is 90 scored the ball passes into the space between 95 the members 7 and 8 being deflected downwardly and directed through the slot 4 and carried by the tongue 12 on to the lever 30 which is operated in a similar manner to the lever 29 hereinbefore described, the lever 30 100 being tilted so as to allow the marble to pass through the opening 18 into the runway 42, the corresponding indicating bar 23 being raised to indicate the corresponding scoring 105 number.

Similarly a marble entering the space between the members 6 and 7 to score an outer is deflected through the slot 4 and carried by the tongue 13 on to the lever 31 which is depressed, the marble passing through the opening 19 into the runway 43 down which it passes to a position against the pin 44. When the score is completed the balls may be removed by simply raising the pin out of the perforations 45. The pin 44 is a spring 110 pin and, therefore, can be sprung to one side 115 in order to allow the upper end of the pin to pass the side of the casing 1.

It will, of course, be understood that when the balls have passed off the levers 29, 30 and 31 through the openings 17, 18 and 19 that the levers relieved of the weight of the balls will return to their normal position and carry the indicating portions of the bars 22, 23 and 24 back to their normal or invisible 120 position, the balls scoring the bull's eyes, the balls scoring the outers and the balls scoring the inners being held in separate runways the score may be easily totaled up at any time during the game or at its completion, 125 130

as each player or side shoots a different colored ball and the runway keeps the balls exposed to the view of the players.

From this description it will be seen that 5 I have devised a very simple form of target in which the individual number scored may be automatically individually indicated and the balls by which such scores are made retained separately so that at the end of or 10 during the scoring the total score may be easily calculated.

What I claim as my invention is.

1. A toy target comprising a casing having a series of concentric openings formed 15 in the front of the casing corresponding to the concentric openings of the target, of a series of movable indicators, one corresponding to each of the target openings, independent projectile receivers into which the projectiles pass from each of the target openings, and means operated by the weight of the projectiles for moving an indicator to the visible position as a projectile passes from a target opening to the receiver and 20 allowing the indicator to return to its normal or invisible position as the projectile passes into the receiver.

2. In a toy target, a casing provided with 25 a series of concentric openings formed in the front of the casing corresponding to the spaces of the target and a series of discharge openings in the back of the casing, downwardly inclined walls extending from the concentric openings of the casing designed 30 to direct the projectiles passing through the openings downwardly to a corresponding discharge opening, a series of movable indicators, projectile receivers corresponding to each of the concentric openings of the target, mechanism for operating independently 35 each of the indicators by the weight of a projectile as it passes from a discharge opening to the receiver.

3. In a toy target, a casing provided with 40 a series of concentric openings formed in the front of the casing corresponding to the spaces of the target and a series of discharge openings in the back of the casing, downwardly inclined walls extending from the concentric openings of the casing designed 45 to direct the projectiles passing through the openings downwardly to a corresponding discharge opening, deflector plates located in a diagonal position between the aforesaid 50 walls and designed to direct the projectiles downwardly, a series of movable indicators, projectile receivers corresponding to each of the concentric openings of the target, and mechanism for operating independently 55 each of the indicators by the weight of a projectile as it passes from a discharge opening to the receiver.

4. In a toy target, a casing provided with 60 a series of concentric openings formed in the front of the casing corresponding to the

spaces of the target and a series of discharge openings in the back of the casing, downwardly inclined walls extending from the concentric openings of the casing designed to direct the projectiles passing through the 70 openings downwardly to a corresponding discharge opening, V-shaped projecting portions located between the upper portions of each wall and designed to direct the projectile laterally, a series of movable indicators, 75 projectile receivers corresponding to each of the concentric openings of the target, and mechanism for operating independently each of the indicators by the weight of a projectile as it passes from a discharge open- 80 ing to the receiver.

5. A toy target comprising a casing having a series of concentric openings in the front wall corresponding to the spaces of the target, a runway corresponding to each 85 of the concentric openings, a stop at the bottom of each runway, means for directing a projectile passing through a concentric opening of the target into a corresponding runway, and a point indicator correspond- 90 ing to each target opening and operated by the passage of a projectile from a target opening to a corresponding runway.

6. A toy target comprising a main casing having a series of concentric openings cor- 95 responding to the divisions of the target, a supplemental casing depending below the main casing, a dividing wall located between the main casing and supplemental casing having a series of discharge openings ex- 100 tends between the main casing and supplemental casing and corresponding to each of the concentric openings of the target and having a series of openings located beneath the main casing, an inclined runway extend- 105 ing downwardly from each of such openings, and means for directing the projectiles from the concentric openings in the front wall through a corresponding discharge opening to a corresponding opening leading 110 to a corresponding runway.

7. A toy target comprising a main casing having a series of concentric openings cor- 115 responding to the divisions of the target, a supplemental casing depending below the main casing, a dividing wall located between the main casing and supplemental casing having a series of discharge openings ex- 120 tends between the main casing and supplemental casing and corresponding to each of the concentric openings of the target and having a series of openings located beneath the main casing, an inclined runway extend- 125 ing downwardly from each of such openings, a lever pivoted at one side of the bottom of each discharge opening and having one end normally extending to a correspond- ing opening leading to a corresponding run- way, a movable indicator carried by the end of the lever, the lever being adapted to be 130

tilted by the weight of a projectile to a position substantially on a line with the opening leading to the runway.

8. In a device of the class described, a casing having a circular opening in the front wall thereof, a series of members carried by the back of the casing and having circular outer ends concentric with the circular open-

ings of the casing, upper and lower downwardly inclined walled portions and outwardly flaring side walled portions. 10
